UNITED STATES PATENT OFFICE.

EDWARD MUELLER, OF INDIANAPOLIS, INDIANA.

DESIGN FOR AN IMITATION SHELL FOR FLOWER-BEDS.

SPECIFICATION forming part of Design No. 12,960, dated June 6, 1882.

Application filed April 10, 1882. Term of patent 3½ years.

To all whom it may concern:

Be it known that I, EDWARD MUELLER, of the city of Indianapolis, county of Marion, and State of Indiana, have invented a new and original Design in Imitation Shells for Bordering Flower and other Garden Beds and Graves, of which the following is a specification, reference being had to the accompanying drawings, forming part thereof.

Figure 1 represents a flower-bed bordered by my newly-designed shell, the concaved side of the shell facing the inside of the bed, the soil filling the concavity of the shell, which firmly holds the soil in place. Fig. 2 represents a plan view of my shell, which may be made of iron or other metal or of burned clay, terra-cotta, or other plastic material allowing it to be formed into the proper shape. The projecting part A, Figs. 2 and 3, being placed in the ground to the line B, holds the shell firmly in place. Fig. 3 represents a sectional view of Fig. 2 at line *x x*.

The concaved part of the shell, as shown in Fig. 3, is to be filled up to C with soil. The convexed part D, as shown in Fig. 2, faces the outside of the bed, and the concaved and convexed portions of the shells in view may be suitably colored in imitation of natural shells, as desired. These three figures are necessary and fully illustrate my design.

What I claim to be new and original, and want to secure by Design Patent, is—

My design for imitation shells for borders of flower and other beds, as herein shown and described.

In witness whereof I have hereunto set my hand this 5th day of April, A. D. 1882.

EDWARD MUELLER.

In presence of—

G. SCHMUCK,
A. W. RITZINGER.
